UNITED STATES PATENT OFFICE.

CARL BAUER, OF WOLFE, WEST VIRGINIA.

TOILET-STAND.

1,156,519.

Specification of Letters Patent.

Patented Oct. 12, 1915.

Application filed February 14, 1914, Serial No. 818,734. Renewed August 31, 1915. Serial No. 48,352.

To all whom it may concern:

Be it known that I, CARL BAUER, subject to the Emperor of Austria-Hungary, residing at Wolfe, in the county of Mercer and State of West Virginia, have invented a new and useful Toilet-Stand, of which the following is a specification.

The present invention appertains to a toilet or wash stand, and aims to provide a novel and improved fixture of that character.

It is the object of the present invention to provide a unique toilet or wash stand, which may be employed in the bed rooms of residences and hotels, or in offices, or elsewhere, and which is so constructed, as to accommodate a wash bowl or basin and pitcher in a peculiar manner, as well as being provided with means for holding various toilet articles as well as articles of wearing apparel, when the stand is not in use for toilet purposes.

A further object of the present invention is to provide a fixture of the character indicated, embodying foldable wash bowl supporting means, and pitcher supporting means, whereby the said means may be brought into and out of operative positions in a novel manner.

It is also within the spirit of the present invention to provide a device of the nature indicated, which will be comparatively simple, compact and inexpensive in construction, which shall be ornamental or artistic in appearance, which may be supported from a wall or upon a floor, and which will be convenient, practical and efficient in its use.

With the foregoing and other objects in view, which will be apparent as the nature of the invention is better understood, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:

Figure 1 is a front view of the improved fixture, portions being broken away, and the wash basin and pitcher supporting means

being swung to inoperative positions. Fig. 55 2 is a horizontal section of the fixture taken on the line 2—2 of Fig. 1, illustrating the wash bowl or basin and pitcher supporting means as folded or swung to operative positions. Fig. 3 is a sectional detail taken on 60 the line 3—3 of Fig. 2.

The present invention embodies as a body or frame, a back, preferably constructed of sheet metal which is japanned or otherwise finished for the purpose of wear and appearance, and including the upper and lower sections 1 and 2. The upper section 1, as illustrated, is of diamond-shaped outline, while the lower section 2 is of trapezoidal form with its smallest end disposed uppermost and coöperating with the lower corner of the upper section 1, whereby the general outline of the back will be somewhat ornamental or artistic. A wire or rod 3 is bent to conform to the contour of the back, and the marginal edge portions of the sections 1 and 2 of the back are bent over the wire or rod 3, whereby the said wire or rod will form a framework or bracing structure for the sheet metal sections 1 and 2. The lower 80 terminals of the wire or rod 3, which are disposed at the lower end of the section 2, are formed into eyes 4, the lower section 2 being provided with the leg extensions 2' adjoining the said eyes 4.

As a means for supporting the back upon a floor, an arcuate base member 5, preferably bent from a wire or rod, has its terminals engaged through the eyes 4 to pivotally connect the base member 5 to the lower end of 90 the back, or to the feet portions 2' of the back section 2, the base member 5, being provided with the doubled portions or stops 6 adjoining the pivotal portions, which stops 6 are adapted to contact with or swing 95 against the feet portions 2' of the back for limiting the upward movement of the base member 5. Thus, when the base member 5 is seated upon a floor or other surface, the back may be supported in an upright position, 100 the lower end of the back resting against the stops or fingers 6 to support the back against swinging forwardly.

As a means for supporting the back from a wall, the wire or rod 3 is formed with a 105 loop 7 at the crest or upper corner of the back section 1, which loop 7 may be engaged over a hook, nail or other member secured

to the wall to which the back is to be applied, whereby the back may be hung upon the said wall.

The upper section 1 of the back is provided with a suitable mirror 8, and with pivoted brackets 9 at the sides of the mirror, carrying candle holders or sockets 10. The section 1 is also provided with comb and brush boxes or receptacles 11 directly below the mirror 8, and with a soap box or receptacle 12 adjoining the lower corner of the said section. The side corners of the section 1 are provided with fixtures 13 including bearings to which are journaled the arms 14 upon which may be hung towels, wash cloths and the like.

Coming to the salient or cardinal features of the present invention, there is provided a pair of coöperating arcuate arms 15 disposed at the upper end of the back section 2, and having the angular portions 16 at their inner ends, the angular portions 16 being provided with hinge butts 17 engaging the wire or rod 3 at the upper end of the back section 2 to pivotally or hingedly connect the arms 15 to the back. The arms 15 are adapted to swing to and from each other, so that when the arms are swung together, as seen in Fig. 2, a wash bowl or basin may be placed thereon, with its rim seating upon the arms 15. The angular portions 16 of the arms 15 serve to space the arcuate or curved portions of the arms 15 sufficiently from the back, so that the wash bowl or basin may be readily supported by the arms. The angular portions 16 also permit the arcuate portions of the arms 15 to swing toward the sides of the back, without the necessity of the arms swinging rearwardly or inwardly beyond the plane of the back.

Disposed below the arms 15, is a pair of side plates or wings 18, which have their upper ends tapered and pivoted or otherwise secured to the arcuate portions of the arms 15, the inner edges of the wings or plates 18 being provided with hinge butts 19 engaging the leg portions of the wire or rod 3. The hinge butts 17 of the arms 15 and the hinge butts 19 of the wings or plates 18 are in alignment, whereby the said arms and plates or wings will swing together, or as unitary structures. As a means for swinging the arms 15 and wings 18, a disk or plate 20 is pivoted or journaled to the back section 2, between the wings 18, by means of a screw 21 passed centrally through the disk or plate 20, the outer end of the screw 21 having a suitable thumb or finger piece 22 whereby the screw may be readily tightened and loosened, and a nut 23 being secured to the back section 2 for the engagement of the screw 21. The disk or plate 20 is provided with a radial lever 24 projecting outwardly through the opening formed between one arm 15 and wing 18. The disk or plate 20

is connected by means of a pair of links 25 with the outer edge portions of the wings 18, whereby when the lever 24 is swung downwardly, the links 25 will be drawn inwardly, so as to swing the wings 18 and arms 15 forwardly to the positions illustrated in Fig. 2. When the lever 24 is swung upwardly, the wings 18 and arms 15 will be swung laterally, or toward the plane of the back, as seen in Fig. 1. The plates or wings 18 also serve as braces for supporting the wash basin or bowl supporting arms 15.

The pitcher supporting means embodies a shelf 26 having its inner edge hinged or pivoted to the lower end of the back section 2, as at 27, the side edges of the shelf 26 having downturned flanges or stops 28 to contact with or seat against the leg portions 2' of the back section 2, for supporting the shelf 26 in a horizontal position, when it is swung downwardly. The shelf 26 is connected by means of a link 29 to the lever 24 or indirectly to the disk or plate 20, whereby when the wings 18 are swung apart, the shelf 26 will be swung upwardly against the back section 2, and when the wings 18 are swung forwardly, the shelf 26 will be swung downwardly to a horizontal position as seen in Fig. 3. When the shelf 26 is swung downwardly, the same may readily support a water pitcher or other articles.

From the foregoing, taken in connection with the drawing, the general features and advantages of the present device will be obvious. When the device is not in use as a wash stand, the wings 18 and arms 15 may be swung apart, whereby the arms 15 may be employed for supporting hats or other articles of wearing apparel, and the towel arms 14 may be employed for supporting coat hangers or other articles. Thus, when the device is not in use as a wash stand, the wings 18 and arms 15 and shelf 26, will be folded against the wall, or approximately into the plane of the back, so as not to encumber the front of the fixture.

When the fixture is to be employed as a wash stand, the wings 18 and arms 15 may be readily swung forwardly to position, by depressing the lever 24, the shelf 26 also being swung downwardly to a horizontal position. Thus the wash bowl or basin may be supported by the arms 15, as above intimated, and the shelf 26 may be employed for supporting a water pitcher. The wings 18 form sides for the shelf 26 to house or inclose the water pitcher, and also brace or support the arms 15, to prevent the arms 15 from sagging under the weight of the wash basin or bowl. After the wash bowl or basin and pitcher have been removed, the parts 15, 18 and 26 may then be swung to idle positions, as above stated.

The parts 15, 18 and 26 may be readily held in the positions to which they are

swung, by tightening the pivot and clamping screw 21, so as to clamp the disk or plate 20 against the back section 2.

Having thus described the invention, what is claimed as new is:—

1. In a wash stand, a back, a pair of co-operating arcuate basin-supporting arms pivoted thereto, brace members secured to the said arms and pivoted to the back, and actuating means carried by the back and operatively connected to the said brace members to swing the same.
2. In a wash stand, a back, a pair of co-operating arcuate basin-supporting arms and a pair of wings pivoted to the back, the arms and wings being secured together, and an oscillatory actuating member carried by the back between the wings and linked thereto.
3. In a wash stand, a back, a shelf and a pair of side wings hinged thereto, and actuating means carried by the back and operatively connected to the said shelf and wings for simultaneously swinging the same to and from the plane of the back.
4. In a wash stand, a back, a shelf and a pair of side wings hinged thereto, actuating means carried by the back and operatively

connected to the said shelf and wings for simultaneously swinging the same to and from the plane of the back, and co-operating arcuate basin-supporting arms carried by the upper ends of the said wings.

5. In a wash stand, a back, a shelf and a pair of side wings hinged thereto, a pair of co-operating basin-supporting arms pivoted to the back and secured to the upper ends of the said wings, and actuating means carried by the back and operatively connected to the said shelf and wings for simultaneously swinging them to and from the plane of the back.

6. In a wash stand, a back, a lower shelf and side wings hinged thereto, basin-supporting means carried by the upper ends of the wings, an oscillatory actuating member carried by the back between the wings, and links connecting the said oscillatory member and the shelf and wings.

In testimony that I claim the foregoing as my own, I have hereto affixed my signature in the presence of two witnesses.

CARL BAUER.
